(57) **CLAIM**

The ornamental design for an electrical vehicle charging station as shown and described.

DESCRIPTION

FIG. 1 is a front right side perspective view of an electrical vehicle charging station.

FIG. 2 is a front elevational view of the electrical vehicle charging station of FIG. 1.

FIG. 3 is a rear elevational view of the electrical vehicle charging station of FIG. 1.

FIG. 4 is a left side elevational view of the electrical vehicle charging station of FIG. 1.

FIG. 5 is a right side elevational view of the electrical vehicle charging station of FIG. 1; and,

FIG. 6 is a top plan view of the electrical vehicle charging station of FIG. 1.

The bottom side of the electrical vehicle charging station is unornamental. The bottom side of charging units and the stand form no part of the claim. Any features not depicted in the figures form no part of the claim.

The broken lines depict portions of the 'electrical vehicle charging station' that form no part of the claimed design.

1 Claim, 6 Drawing Sheets
